UNITED STATES PATENT OFFICE.

HORACE H. TAYLOR, OF SAN FRANCISCO, CALIFORNIA.

DEEP-WELL PUMP.

Application filed December 11, 1922. Serial No. 606,033.

To all whom it may concern:

Be it known that I, HORACE H. TAYLOR, a citizen of the United States, residing at San Francisco, in the county of San Francisco and State of California, have invented new and useful Improvements in Deep-Well Pumps, of which the following is a specification.

The present invention relates to improvements in deep well pumps and has for its primary object to provide a simply constructed, compact and comparatively inexpensive pump which may be cheaply and effectively operated to raise water or other liquids from deep wells or other places where a pump is required, the pumping action being provided through the agency of a fluid pressure from above the well to the pump, which latter is situated below the level of the water in the well, said force actuating the plungers which operate to raise the water or other liquid.

One of the objects of the invention is to provide a pump which as a compact unit, may be readily and easily lowered into a well casing or placed where a pump is to be employed and operated in an extremely effective and reliable manner from the top of the well without the employment of flimsy and complicated control rods, levers or other means of connection between the pump and the top of the well, the operation being automatic and continuous.

The invention further resides in the combination, inter-relation and association of elements of a pump which together provide for simplicity in construction and operation, inexpensiveness and reliability of performance and also to simplify and reduce the cost of deep well pump installation.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the

invention as expressed in the claims may be embodied in a plurality of forms.

Referring to the drawings:

Fig. 1 represents a side elevation of the 55 pump of my invention.

Fig. 2 represents a vertical sectional view of the pump with parts in side elevation and other parts in section.

Fig. 3 represents a fragmentary side elevation of the pump taken at right angles to the showing in Fig. 1.

Fig. 4 represents a fragmentary side elevation of the pump the lower part being broken and shown in vertical section, certain parts of the mechanism being removed for the sake of clearness of illustration.

Fig. 5 represents a cross sectional view on the plane of line 5—5 of Fig. 2.

Fig. 6 represents a cross sectional view 70 taken on the plane of line 6—6 of Fig. 2.

Fig. 7 represents a vertical sectional view taken on the plane of line 7—7 of Fig. 4.

Referring to the embodiment of the invention illustrated in the accompanying 75 drawings, the numerals 1 and 2 designate cylinders of the pump, of which, in this instance there are two. The upper ends of the cylinders are connected with a header member 3 which, by reducing the fitting 4 at its outer end is screwed into the lower end of the pump tubing 5. The lower ends of the cylinders are connected with the lower header member generally designated 6, there being relief ports 7 at said lower 80 ends of said cylinders communicating with the interior of the well A. The entire mechanism of the pump is arranged in compact construction, confined between the headers and pump cylinders and is such 85 that the entire unit may be easily lowered into a well or the like from which liquid is to be pumped. The medium for operating the pump will be some form of hydraulic or fluid pressure and delivered to 90 the pump through a pipe 8 extending along the side of the tubing 5 and pump cylinders to the lower header.

The pipe 8 is connected at its lower end in a screw threaded fitting 9 carried on the upper side of a valve chamber 10 in which chamber a rotary two-way valve 11 is mount-

ed. Leading from the chamber 10 are passageways 12 and 13 which communicate respectively with the pump mechanism for the chambers 1 and 2. When the valve 11 is moved into open position, the operating fluid is delivered through the conduit 12 and when the valve is turned into its other position, the supply of fluid to the conduit 12 is cut off and the fluid then passes through the conduit 12. In this way the pump mechanism of the cylinders 1 and 2 are alternately operated. The conduits 12 and 13 communicate directly with small cylinders 14 and 15 which are provided in the lower header 6. At points just above the ports 16, which ports communicate the conduits with the small cylinders, there are provided in the walls of the small cylinders a plurality of pressure relief ports 17, which are controlled by annular valves 18 and 19 operating within the small cylinders. The annular valves 18 and 19 are fixed by spiders 20 to valve operating rods 21 and 22. These rods are connected at their lower ends by links 23 with the opposite ends of a rocker arm 24. The rocker arm 24 is secured to a stud shaft 25 which stud shaft is carried by the valve 11 and extends outwardly through one wall of the valve chamber 10. By this arrangement, the pressure relief ports 17 are closed when the fluid operating pressure is being delivered to the cylinders, and when the valve is operated to reverse the flow of pressure as will be later described, one of said annular relief valves will open through movement of the rods to which it is connected. The upper ends of the small cylinders 14 and 15 are connected with pressure cylinders 26 and 27 which extend upwardly into the main or pump cylinders 1 and 2, and are open at their upper ends, having a working fit within the cylinders 1 and 2. Co-operating with the cylinders 26 and 27 are piston-like plungers 28 and 29, depending from which plungers are cylinders 30 which telescope and have a working fit upon the cylinders 26 and 27. The lower ends of the cylinders 30 carry a stuffing box or packing arrangement 31 which provides for the effective sealing and working fit of the cylinders 26 and 27. It will be seen that the fluid operating medium under pressure within the cylinders 26 and 27 will cause the plungers 29 to travel upwardly within the pump cylinders 1 and 2.

The liquid to be pumped enters the cylinders 1 and 2 through intake openings 32 provided in the walls of the cylinders 1 and 2 adjacent their upper ends. The header 4 is provided with a wall 33 extending over the upper ends of the cylinders 1 and 2. The wall 33 is provided with outlet ports 34 and 35 which permit the water from the cylinders to pass upwardly from the header and into the tubing 5. Controlling the openings

32 are ring or annular valves 36 and 37 which are fastened by spiders 38 to the lower ends of valve stems 39 and 40. The stems extend upwardly from the annular valves and support valves 41 and 42 for controlling the openings or ports 34 and 35 respectively, said valves being of the upwardly opening type. With this arrangement it will be seen that when the intake ports 32 for the cylinder 1 are open, the valve 41 will be closed and vice versa.

As a means for automatically operating the valve 11, the plungers are provided with depending arms 43 which carry rings 44 that slide upon the rods 21 and 22 and are adapted to abut stop members 45 carried adjacent the upper ends of the rods 21 and 22. It will thus be seen that just before one of the plungers reaches the end of its stroke, one of the rings 44 will engage the stop and cause the rod thereby affected to be lifted whereupon the rocker arm will rock and the valve will be operated to reverse the flow of operating fluid. Coincident with the movement of the rod, the annular valve controlling the pressure relief ports at the lower ends of one of the small cylinders, will be lifted, for example, as shown in Fig. 2. A cushioning spring 46 is provided so as to be engaged by the lower ends of the cylinders 30 on the return stroke of the plunger.

Assuming that the pump as shown in Fig. 2, is installed in a well or other place where it is desired to pump liquid, the pump may be immediately put into operation by the use of some actuating fluid such as water, air or gas, under pressure, which fluid will be conducted to the working cylinders of the pump through the pipe 8. It will be noted that the pump may be lowered into the well easily and without requiring preliminary installation space and that the pump is free from employment of rods, chains or other control elements leading to the top of the well, it only being necessary to use the feed pipe 8 leading from a fluid pressure mechanism such as a pump, not shown, and located at the top of the well.

As shown in Fig. 2, the pump and cylinder 2 has completed its pumping operation and shifted the valve so that the operating fluid from the pipe 8 is delivered through the conduit 12 to the small cylinder 14. When this operation of the valve has taken place, the relief ports 17 of the cylinder 15 are open, due to the raising of the valve 19 and the operating fluid escapes through the ports 17. The liquid below the head of the plunger will be discharged as the plunger recedes through the port 7. When the pressure on the plunger is removed, the valves 42 and 37 gravitate or drop into such position that the valve 42 is closed and the ports 32 are opened. The weight of the valve, also the pressure of the water in the column

standing in the well and in the tube 5, will tend to move the valve and connecting stem therefor, as described. Water then enters the cylinder 2 through the ports 32 and the weight of the water on the plunger, also the natural tendency of the plunger to drop, will cause said plunger to move quickly into its normal position. The spring will cushion the jar as the plunger drops into normal position. Thus the cylinder 2 is thereby automatically rendered ready for another pumping operation. As the operating fluid under pressure passes from the member 12 to and enters the small cylinder 14, it passes up into the cylinder 26 and causes the plunger 28 to rise pushing more of the water standing in the cylinder above the plunger. Upon the first up movement of the plunger 28, the pressure of the water on the under side of the valve 41 causes the valve to lift and this raises the valve 36 and closes the ports 32. The valves 36 and 41 remain respectively in closed and open positions throughout the remainder of the stroke of the piston, and the liquid passes through the port 34 and up through the tube 5 to the top of the well just before the plunger reaches the end of its stroke. The ring 44 encounters the stop 45 and lifts on the rod 21 causing the relief valve 18 to uncover the port 17 and at the same time operating the valve 11 to shut off the supply of operating fluid to the cylinder 1 and turn said supply into the cylinder 2. The valves 36 and 41 and the plunger 28 return to normal position as previously described in connection with the pumping operation. This operation takes place quickly and upon each stroke of the plunger a large quantity of liquid will be raised and pumped out through the tube 5.

A relief valve 50 is arranged in the lower portion of the valve chamber 10 and opens automatically in response to excessive pressure in the chamber 10 so as to relieve the pump parts from excessive strains and possibility of breakage or derangement. This valve may be constructed in any suitable manner provided that it will open automatically when the pressure reaches a predetermined point.

I claim:

1. A deep well pump comprising a cylinder, means providing for attachment of said cylinder to the lower portion of well tubing, said cylinder having a liquid intake opening adjacent its upper end and a liquid discharge opening at its upper end for communicating the cylinder with well tubing, a plunger movable up and down within the cylinder, a fluid pressure supply pipe leading to and arranged to supply fluid under pressure to the cylinder beneath the plunger, an upwardly opening normally closed valve for the liquid intake opening, a stem common to said valve, said valves and stem ar-

ranged such that when the plunger is moved upwardly by operating fluid, the discharge valve will open in response to pressure of liquid in the cylinder and lift the second named valve into position to close the liquid intake opening and a fluid pressure relief valve operating to relieve the fluid pressure in the cylinder when the plunger reaches the end of its stroke. 70

2. A deep well pump comprising pump cylinders, means providing for connecting the upper ends of the pump cylinders with well tubing, said cylinders having liquid intake openings therein and liquid discharge openings, the latter opening into said means of connection, plungers reciprocally mounted within the cylinders, a fluid supply pipe extending through the lower ends of the cylinders, a valve in said chamber which, when moved into one position, will direct operating fluid into one cylinder, and when moved into another position, will direct operating fluid into the other cylinders, said valve being normally in one or the other of said positions, upwardly opening valves controlling the discharge openings, valves controlling the liquid intake openings, stems common to said valves, said conduits having relief ports, valves controlling said ports, and arranged so that one is open at all times and another is closed at all times and means which, when the plunger reaches the end of its stroke will simultaneously open the relief valve and move the first named valve into position to direct operating fluid to the other cylinder, said intake opening and discharge opening valves being arranged so that the latter opens responsive to pressure of water in the cylinder when the plunger is under operation and the former closes the intake opening. 100

3. A deep well pump comprising pump cylinders having liquid intake openings therein, means providing for connection of the upper ends of the cylinders with well tubing, said cylinders having liquid discharge openings opening into the means of connection, valves for said discharge openings, valves for said intake openings, stems common to said valves, said valves and stems being arranged so that when the discharge opening is closed the intake opening will be open and vice versa, plungers operating within the cylinders and which, when moved on their operating stroke will cause the discharge valves to open responsive to pressure of liquid in the cylinder and the intake valves to close, and means for alternately conducting operating fluid under pressure to the cylinders and causing alternating working strokes of the plungers. 110

4. A deep well pump comprising pump cylinders having liquid intake openings therein, means providing for connection of the upper ends of the cylinders with well 120

tubing, said cylinders having liquid discharge openings opening into the means of connection, valves for said discharge openings, valves for said intake openings, stems common to said valves, said valves and stems being arranged so that when the discharge opening is closed the intake opening will be open and vice versa, plungers operating within the cylinders and which, when moved 5 on their operating stroke will cause the discharge valves to open responsive to pressure of liquid in the cylinder and the intake valves to close, and means for alternately conducting operating fluid under pressure 10 to the cylinders and causing alternating working strokes of the plungers, said plungers having tubular extensions, cylinders located within the first named cylinders and upon which the tubular extensions are tel- 15 20 scopically mounted, said second named cylinders receiving the operating fluid.

5. A deep well pump comprising pump cylinders having liquid intake openings therein, means providing for connection of 25 the upper ends of the cylinders with well tubing, said cylinders having liquid discharge openings opening into the means of connection, valves for said discharge openings, valves for said intake openings, stems common to said valves, said valves and stems being arranged so that when the discharge opening is closed the intake opening will be open and vice versa, plungers operating within the cylinders and which, when moved 30 35 on their operating stroke will cause the discharge valves to open responsive to pressure of liquid in the cylinder and the intake valves to close, means for alternately conducting operating fluid under pressure 40 to the cylinders and causing alternating working strokes of the plungers and means operating co-incident with the shifting of the fluid pressure from one cylinder to the other for releasing the pressure in the cylinder in which the plunger has completed its 45 working stroke.

6. The combination with well tubing of cylinders, means for connecting the upper ends of the cylinders with the lower ends of 50 the tubing, said cylinders having liquid intake openings therein adjacent their upper ends and provided with liquid discharge openings at their upper ends, which latter openings extend into the means of connection, upwardly opening valves for closing the discharge openings, valves for closing the intake opening, stems common to the valves, a valve for each cylinder being arranged so that when the discharge valve is 55 closed the intake valve will be open and vice versa, plungers reciprocal in the cylinders, tubular members carried by the plungers, cylinders mounted within the lower portions of the pump cylinders and being telescopied by the tubular members, a pipe for supplying operating fluid under pressure 60 to the last named cylinders, conduits leading from the pipe to the last named cylinders, a valve associated with the pipe and conduits, which when moved from one position to another will cut off the supply of operating fluid from one of said cylinders and cause operating fluid to be delivered to the other of said cylinders, said conduits having relief ports therein, valves for closing said ports, being, one of them open while the other is closed, a rocker arm connected with the valve for controlling the fluid operating pressure, rods connected with the ends of the rocker arm and extending through the conduits into the second named cylinders, stop members on the upper ends carried by 65 70 75 80 85 90 95 100 105 110 115 120 125 130 135 140 145 150 155 160 165 170 175 180 185 190 195 198 199

for supplying operating fluid under pressure to the last named cylinders, conduits leading from the pipe to the last named cylinders, a valve associated with the pipe and conduits, which when moved from one position to another will cut off the supply of operating fluid from one of said cylinders and cause operating fluid to be delivered to the other of said cylinders, said conduits having relief ports therein, valves for closing said ports, being, one of them open while the other is closed, a rocker arm connected with the valve for controlling the fluid operating pressure, rods connected with the ends of the rocker arm and extending through the conduits into the second named cylinders, stop members on the upper ends carried by 70 75 80 85 90 95 100 105 110 115 120 125 130 135 140 145 150 155 160 165 170 175 180 185 190 195 198 199

7. The combination with well tubing of cylinders, means for connecting the upper ends of the cylinders with the lower ends of the tubing, said cylinders having liquid intake openings therein adjacent their upper ends and provided with liquid discharge openings at their upper ends, which latter openings extend into the means of connection, upwardly opening valves for closing the discharge openings, valves for closing the intake opening, stems common to the valves, a valve for each cylinder being arranged so that when the discharge valve is closed the intake valve will be open and vice versa, plungers reciprocal in the cylinders, tubular members carried by the plungers, cylinders mounted within the lower portions of the pump cylinders and being telescopied by the tubular members, a pipe for supplying operating fluid under pressure to the last named cylinders, conduits leading from the pipe to the last named cylinders, a valve associated with the pipe and to the last named cylinders, a valve associated with the pipe and conduits, which when moved from one position to another will cut off the supply of operating fluid from one of said cylinders and cause operating fluid to be delivered to the other of said cylinders, said conduits having relief ports therein, valves for closing said ports, being, one of them open while the other is closed, a rocker arm connected with the valve for controlling the fluid operating pressure, rods connected with the ends of the rocker arm and extending through the conduits into the second named cylinders, stop members on the upper ends carried by 100 105 110 115 120 125 130 135 140 145 150 155 160 165 170 175 180 185 190 195 198 199

the rods, means sliding along the rods beneath the stop member, rods connected with the plunger and supporting said last named means beneath the stop member in position to engage the stop member and lift the first named rod before the completion of the stroke of the plunger, said relief valves being secured to the first named rods and arranged to open upon lifting of the rods and springs in the main cylinders arranged 10 to cushion the tubular members on the return strokes of the plungers.

HORACE H. TAYLOR.
